ELECTRIC SWITCH

Merle R. Swinehart, Milwaukee, Wis., assignor
to Cutler-Hammer, Inc., Milwaukee, Wis., a
corporation of Delaware

Application December 6, 1945, Serial No. 633,112

4 Claims. (Cl. 200—166)

1

This invention relates to antibounce contact mechanisms for electric switches.

The invention has among its objects to provide an improved contact mechanism for electric switches which operates to frictionally dissipate the kinetic energy present in the moving switch parts when the same are moved into circuit closing position to thereby minimize separation of the switch contacts by rebound after they have once engaged.

Another object is to provide an antibounce contact mechanism of the aforesaid character which is simple and rugged in construction, positive and reliable in operation and which is capable of being readily applied to existing control switches of various types and particularly spring closed electromagnetically operated switches.

Various other objects and advantages of the invention will hereinafter appear.

The accompanying drawing illustrates an embodiment of the invention which will now be described, it being understood that various modifications may be made in the embodiment illustrated without departing from the spirit and scope of the appended claims.

In the drawing,

Figure 1 is a side elevational view of an electromagnetic switch embodying the invention;

Fig. 2 is a fragmentary end elevational view of switch shown in Fig. 1 illustrating one of the contact mechanisms thereof;

Fig. 3 is a front elevational view of the contact finger and operating armature shown in Fig. 1, and

Fig. 4 is a sectional view on line 4—4 of Fig. 3.

Referring to Fig. 1, a contact mechanism embodying the invention is shown in connection with an electromagnetic switch of the type disclosed in the patent to C. Stansbury et al., No. 2,205,676, issued June 25, 1940. Briefly described this switch is provided with an operating coil 1 having a center core member 2 which is mounted midway between the side arms of a U-shaped magnet frame 3. Frame 3 is secured to an insulating panel 4 and core member 2 is provided with an elongated pole shoe 5 for attracting a pair of contact carrying armatures which extend in parallel relation across the gap between the side arms 3^a and 3^b of said frame. These armatures, one of which is designated by reference numeral 6, are pivotally mounted upon a bracket 7 secured to arm 3^a of the magnet frame and each of said armatures has a biasing spring 8 associated therewith for moving the free end thereof away from the front end of magnet frame arm 3^b. Upon energization of coil 1 the contact carrying armatures 6 are attracted into engagement with a non-magnetic stop 9 secured to the outer end of magnet frame arm 3^b against the action of their associated springs 8, and said springs may be ad-

2

justed to provide for release of said armatures at different current values in coil 1.

The armature 6 illustrated in Fig. 1 has normally closed contacts 10 and 11 associated therewith. Contact 10 is fixed to an L-shaped bracket 12 which in turn is secured to an insulating block 13 mounted upon magnet frame arm 3^b. Bracket 12 is electrically connected by a lead 14 to a binding post 15 mounted upon base 4.

10 Contact 11 is mounted upon one end of a finger 16 and said finger is grooved adjacent its opposite end to provide a transverse bearing portion 17 of convex shape on the rear face thereof. Armature 6 has a bearing plate 18 fixed to the front face thereof by screws 19 and as illustrated in Figs. 3 and 4 said plate is provided with a slot 29 having bearing projections 28—28 formed on opposite sides thereof for receiving the bearing portion 17 of finger 16. The bearing portion 17 of finger 16 is provided with an opening for receiving a pin 21 which is fixed to armature 6 and disposed at right angles thereto. Pin 21 carries an elongated sleeve 22 which is slidable thereon and is provided with a flange projection 23 for engaging the front face of contact finger 16 at points on opposite sides of the bearing portion 17. Sleeve 22 is pressed against the front face of contact finger 16 by a coil spring 24 held under compression between the flange 23 of said sleeve and a cup washer 25 secured to the outer end of pin 21 by a cotter pin 26. Bearing plate 18 has a pin 27 fixed thereto which extends through an opening in finger 16 to hold said finger against lateral movement with respect to armature 6. Finger 16 is electrically connected to bracket 7 by a flexible pigtail connection 28.

As is apparent from the foregoing, spring 24 acts through the medium of sleeve 22 to hold the bearing portion 17 of finger 16 in engagement with the bearing projections 28—28 on bearing plate 18. Also as is apparent from Fig. 4, the flange 23 on sleeve 22 engages the outer face of finger 16 to yieldingly hold said finger in parallel relation with respect to the front face of armature 6, as shown in Fig. 4.

When armature 6 is released from its attracted position contact 11 is moved into engagement with contact 10 under the action of spring 8 to establish circuit between bracket 7 and binding post 15. Upon engagement of said contacts finger 16 yields against the biasing action of its associated spring 24, as shown in Fig. 1, to permit overtravel of armature 6 with respect to said finger by inertia of the moving switch parts. During this overtravel of armature 6, bearing portion 17 of contact finger 16 is rocked with respect to its associated bearing projection 28—28 and sleeve 22 is moved outwardly upon its associated pin 21 against the action of spring 24. Thus upon overtravel of armature 6 part of the kinetic energy

present in the moving switch parts is stored in spring 24 and the remainder is dissipated by frictional losses which occur between bearing portion 17 and bearing projections 20-20 between finger 16 and sleeve 22 and between said sleeve and the pin 21. These frictional losses are of relatively large value, and when overtravel of armature 6 is stopped the energy stored in spring 24 is barely sufficient to restore finger 16 to normal position with respect to said armature when the latter is again moved into its attracted position. In practice it has been found that frictional dissipation of a large part of the energy present in the moving switch parts during overtravel of armature 6 beyond the position shown in Fig. 1 tends to minimize rebound of contact 11 when the same is moved into engagement with contact 10.

What I claim as new and desire to secure by Letters Patent is:

1. In an electric switch, in combination, a movable operating member biased to move in one direction, a contact finger fulcrumed at one end upon said operating member, a stationary contact to be engaged by the opposite end of said finger upon biased movement of said operating member into a given position, and a spring pressure device associated with said finger at its fulcrum point, including a supporting pin fixed to said operating member and extending through an opening in said finger at its fulcrum point, a compression spring carried by said pin, a sleeve slidable on said pin and held in engagement with said finger under the action of said spring to normally hold said finger and said operating member in a given angular relation when said finger is disengaged from said stationary contact and to permit inertial overtravel of said operating member beyond said given position upon movement of said finger into engagement with said stationary contact, said sleeve and the fulcrum connection between said operating member and said finger acting during overtravel of said operating member to effect frictional dissipation of the energy present in said operating member and said finger at a rate to minimize rebound of said finger when the same is moved into engagement with said stationary contact.

2. In an electric switch, in combination, a movable operating member biased to move in one direction, a contact finger supported at one end upon said operating member by an open pivotal bearing, a stationary contact to be engaged by the opposite end of said finger upon biased movement of said operating member into a given position, a spring device associated with said finger at its bearing point to hold the same in assembled position upon said operating member, said device including a supporting pin fixed to said operating member and extending through an opening in said finger at its bearing point, a compression spring carried by said pin and a sleeve slidable on said pin and held in engagement with said finger under the action of said spring to subject said finger to a biasing force which normally holds the same in a given angular position with respect to said operating member, said sleeve being movable upon said pin against the action of said spring to permit inertial overtravel of said operating member beyond said given position when said finger engages said stationary

contact and said open pivotal bearing and said sleeve acting during such overtravel of said operating member to effect frictional dissipation of energy present in said operating member and said finger at a rate to minimize rebound of said finger when the same is moved into engagement with said stationary contact.

3. In combination, a stationary contact, a co-operating contact finger, a movable supporting and actuating member for said finger and a connection between said finger and said member comprising a bearing portion on said finger and cooperating bearing projections on said member arranged for sliding engagement with said bearing portion and further comprising spring pressure means carried by said movable member and bearing upon said finger at said bearing portion with balanced forces, to effect a highly frictional connection between said bearing portion and its cooperating bearing projections and also to rock said finger into relationship with said supporting and actuating member such as to provide a play therebetween to be taken up against the bias of said spring pressure means when said member is operated for engagement of said finger with said stationary contact, said spring pressure means being positioned so that the major portion of its pressure is used to effect friction in the connection between said finger and said movable member and so that only a small amount of its pressure is used in rocking said finger into relationship with said movable member, and said spring pressure means comprising parts affording high frictional resistance to take-up of such play between said finger and said member thereby to minimize tendency of rebound of said finger upon engagement with said stationary contact.

4. In an electric switch having a stationary contact, a co-operating contact finger and a movable supporting and actuating member for said contact finger, a connection between said member and said finger comprising a bearing surface on said movable member, a cooperating bearing portion on said finger arranged for sliding engagement with said bearing surface, and spring pressure means carried by said movable member and engaging said finger concentrically with said bearing portion in manner that the major part of the energy of said spring pressure means will be used to effect highly frictional resistance in said connection and only a small part of said energy will be used to return said finger to normal position with respect to said movable member when not in engagement with said stationary contact, said spring pressure means itself comprising relatively movable parts having high frictional resistance to their relative movement.
